UNITED STATES PATENT OFFICE.

BARTOLOMEO DE MATTIA, OF GARFIELD, NEW JERSEY, ASSIGNOR TO F. A. CIGOL
RUBBER CO., OF PATERSON, NEW JERSEY.

DESIGN FOR A RUBBER BALL.

45,741.

Specification for Design.

Patented May 12, 1914.

Application filed November 17, 1913. Serial No. 801,542. Term of patent 7 years.

To all whom it may concern:

Be it known that I, BARTOLOMEO DE MATTIA, a citizen of the United States, residing at Garfield, in the county of Bergen and State of New Jersey, have invented a new, original, and ornamental Design for Rubber Balls, of which the following is a specification, reference being had to the accompanying drawing, forming part thereof.

Figures 1 and 2 are plan views of the ball taken from different angles.

I claim:

The ornamental design for a rubber ball, as shown.

BARTOLOMEO DE MATTIA.

Witnesses:

P. DE MATTIA,
L. DE PELLEGRIN.
